HYDRAULIC TRANSMISSION

Filed July 8, 1919

Witness:
Richard J. Jacker

Inventor:
Edward G. Jacker

UNITED STATES PATENT OFFICE.

EDWARD G. JACKER, OF CHICAGO, ILLINOIS, ASSIGNOR OF ONE-HALF TO VINCENT BENDIX, OF CHICAGO, ILLINOIS.

HYDRAULIC TRANSMISSION.

Application filed July 8, 1919. Serial No. 309,458.

My invention relates to means for the transmission of power and the objects of my improvements are first, to eliminate wearing parts; second, to prevent noise; third, to make the device self lubricating; fourth, to make a simple, cheap and durable construction and other features to become apparent from the description to follow.

Heretofore power has been transmitted by means of belts, chains and gears and considerable mechanism was necessary to attain the desired result. Necessarily this mechanism required lubrication and in time the parts would become worn and require to be replaced or repaired. By the use of my invention these objectionable features are eliminated since it consists of a pump for driving and a motor to be driven. Preferably the liquid used in the pump and motor is a lubricating oil and the pump and motor are preferably of a rotary type. To decrease the speed and increase the power, the pump is made smaller than the motor, and of course to increase the speed and decrease the power, the pump is made larger than the motor.

To describe my invention so that others versed in the art to which it pertains can make and use the same, I have illustrated the same on the accompanying sheet of drawing, forming a part of this specification and in which:

Figure 1, is a plan view of a hydraulic transmission embodying my invention; Fig. 2, is an end view of the same; Fig. 3, is a cross sectional view taken on line 3—3 of Fig. 1, viewed in the direction indicated by the arrows; Fig. 4 is a similar view taken on line 4—4 of Fig. 1, viewed in the direction indicated by the arrows; and Figs. 5 and 6 are similar views showing the valves in different positions.

Similar reference characters refer to similar parts throughout the several views.

The mechanism is preferably contained in a one piece cast frame 7 in one end of which is mounted to operate the large driven rotary motor 8 and in the other end of which is mounted to operate the small driving rotary pump 9. The said motor 8 and pump 9 operate in separate compartments which are separated by the solid wall 10. The smaller compartment is closed by a head 11, secured to the frame, 7, by suitable

bolts, and the larger compartment is closed 55 by a head, 12, secured to the frame, 7, by suitable bolts.

Referring to Fig. 4, it will be noted that the intake port 13 of pump 9 is provided with a valve 14 and the outlet port 15, of 60 said pump 9 is provided with a valve 16, and as seen in Fig. 2, said two valves are connected to act in unison. Suitable ports or passages are cored out in the cast frame, 7, to make proper connections.

A passageway 17 connects the inlet 13 and the outlet 15 on one side of pump 9 as viewed in Fig. 4, and a passageway 18 connects said inlet 13 and outlet 15 on the other side of pump 9. A branch passageway 19 connects 70 the passageway 17 to one side of motor 8 and a branch passageway 20 connects the passageway 18 to the other side of the motor 8. The valves 14 and 16 it will be noted are so constructed that when placed in central 75 position, as shown in Fig. 5, the fluid or oil is free to pass from the outlet port 15 through both passageways 17 and 18, and thence into the pump 9 through inlet port 13.

Thus when the valves 14 and 16 are in the position shown in Fig. 4, the rotation or operation of pump 9 will rotate or operate the motor 8 in one direction and when the said valves 14 and 16 are in the position shown in Fig. 6, the rotation or operation of pump 9 will rotate or operate the motor 8 in the opposite direction, and when said valves 14 and 16 are in the position shown in Fig. 5, the rotation or operation of pump 9 will not operate the motor 8 because all the fluid or oil forced out through the outlet port 15 is free to pass through passageways 17 and 18 back into the inlet port 13.

When the valves 14 and 16 are in the position shown in Fig. 4, the course of the fluid or oil is from pump 9 through outlet port 15, through valve 16, through a part only of passageway 18, through passageway 20, to motor 8, thence through passageway 19, through a part only of passageway 17, through valve 14, and thence through the inlet port 13 and back to pump 9.

When the valves 14 and 16 are in the position shown in Fig. 6, the course of the fluid or oil will be from pump 9, through outlet port 15, through valve 16, through a part only of passageway 17, through passageway

19 to motor 8, thence through passageway 20, through a part only of passageway 18, through valve 14, and thence through inlet port 13, and back to pump 9.

5 Thus while pump 9 is constantly rotating or operating in one direction the motor 8 can be driven forward, or reverse, or not driven in either direction by simply manipulating the valves 14 and 16.

10 The head 11 is pierced by shaft 21 rigidly keyed to one of the two gear wheels forming pump 9 and is connected to the source of power. The head 12 is pierced by the shaft 22 rigidly keyed to one of the two gears 15 forming the motor 8 and is connected to the part or mechanism to be driven.

The valve 16 has a hand lever 23 secured thereto by means of which said valve is operated. A connecting link 24 is pivoted 20 at one end to the hand lever 23 and at the other end to the free end of a crank arm 25 secured to valve 14. Said parts are so arranged and constructed that the two valves 14 and 16 will always be moved in unison by 25 the hand lever 23.

By this improved mechanism it is possible to provide any desired ratio between the pump and the driven motor, and it is therefore applicable to any mechanism whatever.

30 I prefer to provide an air pocket 26 in connection with the passages for oil to pre-

vent pounding or sudden strains on the mechanism when operating.

It will be understood that if it is desired to increase the speed from the driving pump 35 to the motor, it is only necessary to make the motor 8 the driving pump and pump 9 the driven motor.

Having thus fully described my invention what I claim as new and desire to secure by Letters Patent of the United States is:—

In a device of the class described, a casing of a flattened cylindrical shape having both ends closed and provided on its interior with a pump chamber and a motor chamber 45 and a passageway entirely surrounding the pump chamber and conforming to its contour, short passageways centrally disposed in the flattened sides of the casing forming 50 communication between the first named passageway and the pump chamber, valves at the junctions of said passageways to control the passage of fluid therethrough connected to operate in unison and other passageways connecting said first named passageway to the inlet and outlet sides of the motor chamber.

In testimony whereof I have signed my name to this specification this 31st day of May, 1919 at Chicago, Illinois.

EDWARD G. JACKER.
